UNITED STATES PATENT OFFICE.

STEPHEN G. JOHNSTON, OF BARBOURSVILLE, WEST VIRGINIA.

KILN.

1,253,182.

Specification of Letters Patent. Patented Jan. 8, 1918.

Application filed January 29, 1916. Serial No. 75,157.

To all whom it may concern:

Be it known that I, STEPHEN G. JOHNSTON, a citizen of the United States, residing at Barboursville, in the county of Cabell and State of West Virginia, have invented new and useful Improvements in Kilns, of which the following is a specification.

This invention relates to kilns, and it has particular reference to that type of kilns in which gas is used as a fuel.

The invention has for its object to produce a kiln which may be fired along the center, as well as along the sides, as has heretofore been customary in kilns where gas is utilized as a fuel, thereby enabling the heat to be thoroughly equalized within the kiln and also promoting the facility with which the temperature may be regulated and varied.

20 A further object of the invention is to produce a simple and improved center fired gas-heated kiln of a construction whereby the gas main, as well as the means for supplying atmospheric air to support combustion will be safeguarded and made ready of control and regulation.

25 A further object of the invention is to simplify and improve the construction and arrangement of the burners as well as the means for supplying gas and air to support combustion.

30 With these and other ends in view which will readily appear as the nature of the invention is better understood, the same consists in the improved construction and novel arrangement and combination of parts which will be hereinafter fully described and particularly pointed out in the claim.

35 In the accompanying drawings has been illustrated a simple and preferred form of the invention, it being, however, understood that no limitation is necessarily made to the precise structural details therein exhibited, but that changes, alterations and 40 modifications within the scope of the claim may be resorted to when desired.

In the drawings,—

45 Figure 1 is a vertical sectional view taken longitudinally through a kiln constructed in accordance with the invention.

Fig. 2 is a transverse sectional view taken on the line 2—2 in Fig. 1.

50 Fig. 3 is a sectional detail view, enlarged, of one of the burners showing the means for supplying gas and atmospheric air.

Fig. 4 is a transverse sectional view taken on the line 4—4 in Fig. 3.

Fig. 5 is a transverse sectional view illustrating a modified form of the invention.

Fig. 6 is a longitudinal sectional view extending part way through the kiln and illustrating the modified form of the device.

Fig. 7 is a perspective detail view showing a portion of the air duct, the gas pipe and the angle cock, together with the shutters for regulating the admission of air.

Corresponding parts in the several figures are denoted by like characters of reference.

The improved kiln comprises the side walls 15, end walls 16 and roof 17, the side walls being pierced along their lower portion by rows of eyes 18. Rows of burners B are arranged exteriorly of the kiln adjacent to the eyes or openings 18, and these burners may be of the general construction shown in my previous Patent No. 1,134,863, dated April 6, 1915.

Extending longitudinally of the kiln, a short distance below the floor level 19, is an air duct 20 which may be constructed of tiling, brick work or the like, said duct being provided at intervals with upwardly extending branches 21 which may likewise be constructed of clay tiling or the like, and which may be connected with the main duct 20 in any convenient manner. The branches 21 are permitted to extend a short distance, say from two to three inches above the floor level, and the duct 20 will preferably be laid from 18 to 24 inches below the floor level. Extending the branch pipes 21 above the floor level, as just described, not only prevents dirt and rubbish from dropping through said branch pipes to the main air duct where obstructions would thus presently be found, but it also lessens the liability of the gas issuing through said branch pipes from being interfered with by conflicting air currents entering through the eyes 18 and interfering with the ready combustion of the gas mixture.

Extending through the air duct 20 and supported in the lower portion thereof is a gas main 22 having upwardly extending gas tubes 23 which are disposed axially with respect to the ducts or branches, said gas tubes being of such length as to project into the lower ends of the ducts 21. Each gas tube is provided with a cap 24 through which one or more apertures 25 will be drilled for the escape of the gas. The

gas main is provided with a controlling valve 26. The air duct 20 may be opened for the intake of atmospheric air at one or both ends. In Fig. 1 of the drawings one end of the air duct which is thus open for the intake of air opens into a ditch 27.

As will be seen by reference to Fig. 1 of the drawings, the burners are arranged in alinement with the eyes 18 in the side walls 10 of the kiln, said eyes being obstructed or left open, as may be required, according to the character of the work to be done and as may be preferred at various stages of the operation. When said eyes are left unobstructed 15 they will constitute air intakes, and the air admitted through said eyes may be utilized either to assist in supporting combustion or to assist in cooling the contents of the kiln. While the process of burning is going on the 20 products of combustion will escape in the customary manner through openings below the roof of the kiln.

By extending the gas main through the air duct, as herein described, and providing 25 the air duct with upwardly extending branches that surround the upper ends of the gas tubes communicating with the gas main, the gas will be provided with a proper admixture of air to support combustion, it 30 being evident that by the controlling valve 26 the quantity of gas escaping through the gas tubes will be controlled. Under the arrangement shown and described the row of burners will extend longitudinally and centrally 35 through the kiln, the contents of which will thus be heated equally and in a more thorough and effective manner than by the means heretofore employed.

It may at times be desirable to produce 40 a construction whereby the flow of gas to the burners located midway between the sides of the kiln may be individually controlled, as well as the supply of air to form a proper mixture with the gas. When this is the case 45 the construction illustrated in Figs. 5 and 6 is resorted to. By this construction a plurality of air pipes 30 are provided, said pipes being laid below the floor of the kiln and extending from one side to a point midway 50 between the sides of the kiln. These air pipes or ducts are closed at their inner ends and are provided near their inner ends with

upwardly extending branches 31 that terminate a short distance above the floor of the kiln. The gas pipe or main 32 that supplies the burners B at the side of the kiln is provided with T-couplings 33 from each of which a feed pipe 34 extends to the gas tube 35 that projects upwardly into the lower end of the upwardly extending branch 60 pipe 31 that communicates with the duct 30. The flow of gas through the pipe 34 may be controlled by an angle cock 36, and the flow of air through the duct 30 may be controlled by means of shutters 37 at the outer end of 65 the duct 30. It is evident that by this construction the flow of gas and air to the burners extending centrally through the kiln may be individually controlled, thus enabling the heat from the center burners to 70 be absolutely regulated.

Having thus described the invention, what is claimed as new, is:—

In a gas kiln having its sides provided 75 with openings, an exteriorly arranged longitudinally extending gas supply pipe at each side of the kiln, individually controllable air supply pipes disposed at the bottom of said openings and extending horizontally into the kiln, individually controllable gas tubes 80 connected with said gas supply pipes and extending into said air pipes, horizontally arranged individually controllable air supply pipes extending transversely into the kiln beneath the floor thereof and disposed 85 below and in alinement with said first named air supply pipes and terminating at the longitudinal center line of the kiln, vertical branch pipes communicating with the inner ends of said second named air pipes and extending 90 into the kiln in alinement with said first named air pipes, individually controllable gas pipes in said last named air pipes and communicating with one of said gas supply pipes and gas tubes connected with 95 said last named gas pipes and extending into said vertical branch pipes.

In testimony whereof I affix my signature in presence of two witnesses.

STEPHEN G. JOHNSTON.
